UNITED STATES PATENT OFFICE

150,236

DESIGN FOR A GAME OF SKILL

Arthur H. Kneser, Milwaukee, Wis.

Application February 12, 1947, Serial No. 136,858

Term of patent 3½ years

(Cl. D34—5)

To all whom it may concern:

Be it known that I, Arthur H. Kneser, a citizen of the United States, residing at Milwaukee, in the county of Milwaukee and State of Wisconsin, have invented a new, original, and ornamental Design for Game of Skill, of which the following is a specification, reference being had to the accompanying drawing, forming a part thereof.

In the drawing:

Fig. 1 is a side elevation of a game of skill, showing my new design;

Fig. 2 is a rear view of the game of skill; and

Fig. 3 is a front and side perspective view thereof.

The dominant and characteristic features of

my design are shown by means of solid lines in the drawing.

I claim:

The ornamental design for a game of skill, substantially as shown and described.

ARTHUR H. KNESER.
